UNITED STATES PATENT OFFICE.

AUGUST GOERTZ AND FREDERICK GOERTZ, OF NEWARK, NEW JERSEY, ASSIGNEES TO
AUGUST GOERTZ & CO., A CORPORATION OF NEW JERSEY.

LOCK.

Application filed August 24, 1923. Serial No. 659,085.

To all whom it may concern:

Be it known that we, AUGUST GOERTZ and FREDERICK GOERTZ, citizens of the United States, residing at Newark, in the county of Essex and State of New Jersey, have invented certain new and useful Improvements in Locks; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in locks; and, the present invention has reference, more particularly, to a novel construction of lock for use more especially with trunks, suit-cases, travelling bags, and the like.

The present invention, therefore, has for its principal object to provide a novel and simply constructed lock of the general character hereinafter more fully set forth, and one in which the various parts are easily and quickly assembled, and are of such arrangement and construction, so that a neat and an effectively operating as well as a readily operated lock-construction will be the result.

Other objects of this invention not at this time more particularly enumerated will be clearly understood from the following detailed description of the present invention.

With the various objects of the present invention in view, the said invention consists, primarily, in the novel lock hereinafter more fully set forth; and, the said invention consists, furthermore, in the novel arrangements and combinations of the several devices and parts, as well as in the details of the construction of the said parts, all of which will be more fully described in the following specification, and then finally embodied in the clauses of the claims, which are appended to and which form an essential part of this specification.

The invention is clearly illustrated in the accompanying drawings, in which:

Figure 1 is a front elevation of a lock made according to and embodying the principles of the present invention, showing in connection therewith fragmentary portions

of the portions of a trunk, or the like, to which the respective parts of the lock are secured; and Figure 2 is a vertical sectional representation of the same, said section being taken on line 2—2 in said Figure 1.

Figure 3 is a sectional representation, taken on line 3—3 in said Figure 2, looking in the direction of the arrow x; Figure 4 is a plan view of the main body-plate of the lock; and Figure 5 is a side view of a shell or casing forming a part of the lock, and oscillatorily disposed upon said body-plate.

Figure 6 is a view, partly in elevation and partly in section, of the lock, said view illustrating the assembled parts of the lock in their locked relation; Figure 7 is a similar view of the various parts of the lock, illustrating the first step for bringing the parts of the key-operated lock-mechanism into their unlocked relation; and Figure 8 is another similar view of the same parts, illustrating the movable members of the lock in their released and manipulated positions for the release of the lock-hasp from its engaged relation with the lock-mechanism.

Figure 9 is a detail sectional representation, taken on line 9—9 in Figure 2; and Figure 10 is a detail sectional representation, taken on line 10—10 in said Figure 2.

Figure 11 is a perspective view of the spring-controlled and key-operated bolt of the locking mechanism of the device.

Figures 12 and 13 are sectional representations similar to the section represented in said Figure 10, the respective views illustrating different positions of the hasp-engaging catch of the lock with relation to the hasp.

Figures 14, 15 and 16 are views similar to those represented in Figures 6, 7 and 8, showing a slightly modified construction of the lock.

Similar characters of reference are employed in all of the figures of the said drawings, to indicate corresponding parts.

Referring now to the said drawings, the reference-character 1 indicates a fragmentary portion of the body of a trunk, or the like, and 2 indicates a portion of the lid of the same, said lid being shown with the usual marginal valance 3.

Suitably secured upon said valance, by means of rivets 4, or other suitable fastening

means, is a suitably shaped body or element, as 5, with which is pivotally connected in any usual manner, as at 6, an ornamental hasp-plate, as 7, which is provided at its 5 lower end-portion with the usual and rearwardly extending hasp-lug 8.

The lock-body proper comprises a suitably formed ornamental plate 9 which is secured by means of rivets 10, or other 10 suitable fastening means, in the proper position upon the body 1 of the trunk, or the like. As shown more particularly in Figure 4 of the drawings, the said body-plate 9 is provided with suitably disposed perforations, as 11, for the reception of the said rivets 10, and is also formed with a circular depression, as 12, the purpose of which will presently be more fully described. The wall-portion 13 of the said body-plate 9 15 is formed within said depression with lug-receiving slots, as 14. Other slots, as 15 and 16 may also be provided. The said wall-portion 13 is also made with a hole or perforation 17, and the said wall-portion 20 25 is further provided with upwardly projecting and suitably formed studs or posts, as 18, 19 and 20.

The reference-character 21 indicates a cylindrical shell or member of such size 30 that it may be oscillatorily fitted in the depression 12 of said body-plate 9, the said shell, in its wall-portion 22 being formed with marginal slots 23, also with an elongated opening or slot, as 24, see Figure 10, 35 into and through which the studs or posts 18 and 19 project, and with another slot or opening, as 25, into and through which the posts 20 projects.

Extending upwardly from the wall-portion 22 of the said oscillatorily disposed shell or member 21 is a lock-stud or post 26, the said wall-portion 22 being provided with another stud or post 27. Attached to this 40 stud or post 27 is one end of a coiled spring 28, the other end of said spring being secured to the stud or post 20 which extends through the slot or opening 25, for normally maintaining the said shell or member 21 in its initial position indicated in Figures 3, 45 6 and 7 of the drawings.

The wall-portion 22 of the said shell or member 21 has also secured thereon, by means of rivets 29, or other suitable fastening means, in the proper position, a plate 30 from which extends in an upward direction a hook-shaped or similar member, as 31, with which the hasp-lug or loop 8 of the hasp-plate 7 is adapted to be brought into holding engagement, in the manner and 50 for the purposes hereinafter more fully described. The said plate 30 may also be provided with a rib 32, in alinement with said hook-shaped member 31, and having its marginal edge 33 inclining in a downward direction toward the upper face of the said plate

30 and toward the said hook-shaped member 31, substantially as illustrated in Figures 9, 13 and 14 of the drawings.

Suitably disposed within the said oscillatory shell or member 21 is another cylindrical shell or member, as 34, the said shell 34 having a reversed relation to the said shell 21, when concentrically arranged within the latter shell, so that the two shells provide a box or case, as will be evident, 75 the portion 35 of the said shell 34 forming a top-plate for the said box or case thus produced. The said top-plate 35 is provided with an elongated opening or slot, as 36, for reception of the previously mentioned hasp-lug or loop 8. In the proper location, the said top-plate 35 is also made with a hole or perforation 37 into which the key-receiving end of a key-post of a locking mechanism, to be presently described, extends, as will be evident from an inspection of the several figures of the drawings. In order that the said shell or member 34 may be fixed against rotation within the oscillatory shell or member 21, the said shell 34, as will be seen from Figure 5 of the drawings, is provided with suitably formed marginal fastening lugs, as 38, which are passed through the marginal slots 23 of the shell 21 and then inserted and properly upset 95 or riveted over in the correspondingly located slots 14 with which the wall-portion 13 of the body-plate 9 is provided. From an inspection of the several figures of the drawings, it will be understood that while the shell or member 34 is thus secured in a non-rotatable position, owing to the lengths of the various slots in the wall-portion 22 of the shell or member 21, the latter shell 100 may be oscillated back and forth, such movement, however, being limited by the position of the stud or post 20 and the slot 25.

Within the said box or casing thus produced by the two shells or members 21 and 34 is suitably secured any desired construction of casing or box, comprising a main body, as 39, which is provided in its wall-portion 40 with suitably disposed holes or perforations 41, so as to be centered in a 110 fixed position upon the previously mentioned studs or posts 18 and 19. Secured upon said main body 39 is a cover-plate 42, and in the opposite side-walls 43 are openings, as 44 and 45, in which is movably disposed a suitably formed bolt, as 46. A 115 spring 47 is employed for maintaining the operative relation of the said bolt across the chamber of the said lock-casing or box, as will be evident. Furthermore, the said lock-casing or box is provided with a suitable key-post, as 48, for reception of a key 49 by means of which the said bolt 46 is adapted to be moved back and forth across the said lock-casing or box, so as to be brought into or out of the path of the move- 120 125 130

ment of the previously mentioned lock-stud or post 26, as will be clearly understood from an inspection of Figures 3, 6, 7, 14, 15 and 16 of the drawings. As will be evident from Figures 2, 4, and 10 of the drawings, the said key-post 48 has its respective end-portions rotatably disposed in the previously mentioned perforations or holes 17 and 37, its shank extending into and through an elongated opening or slot 50, as shown in Figure 10, with which the wall-portion 22 of the oscillatory shell or member 21 is provided, and that thereby the oscillatory movement of the said shell or member 21, when the bolt 46 has been brought into its unlocked relation with the lock-stud or post 26, will not be interfered with, as will be clearly understood.

Referring now to the modified construction shown in Figures 14, 15 and 16 of the drawings, the lock-construction, in general, is substantially the same as that shown in said Figures 1 to 13 inclusive, except that the arrangement of the elongated opening 25, and the spring 28 and posts 20 and 21, is reversed from that shown in said last-mentioned figures, the oscillatory shell or member 21 being formed in its wall-portion 22, in lieu of the slot 25, with an elongated opening or slot 51, and with a post 52. In lieu of the post 20, the wall-portion 13 of the plate 9 is provided with an upwardly extending post 53, which projects through said opening or slot 51, and in lieu of the connecting spring 28, a spring 54 is disposed between and is connected at its ends with the respective posts 52 and 53, so as to serve the same purposes as said spring 28. Instead of the form of plate 30 with its hook-shaped member 31 and rib 32, the wall-portion 22 of the oscillatory shell or member 21 may be provided with a hook-shaped post, as 55, with which the hasp-lug or loop 8 of the hasp-plate 7 is adapted to be brought into separable holding engagement, as will be fully understood.

The construction and operation of the remaining devices and parts of the lock represented in said Figures 14, 15 and 16 being the same as the construction and operation of the devices and parts of the lock illustrated in said Figures 1 to 13 inclusive, any further description of the same is deemed unnecessary.

Of course, we are fully aware that other changes may be made in the general arrangements and combinations of the several devices and parts, as well as in the details of the construction of the said parts, without departing from the scope of the present invention, as set forth in the foregoing description, and as defined in the clauses of the claims which are appended to the said specification. Hence, we do not limit our invention to the exact arrangements and

combinations of the various devices and parts, as described in said specification, nor do we confine ourselves to the exact details of the construction of the said parts, as illustrated in the accompanying drawings. 70

We claim:—

1. A lock comprising a main base-plate, a shell oscillatorily disposed upon said base-plate, a second shell within and having a fixed relation to said oscillatory shell, a hasp-loop engaging member upon said oscillatory shell, a hasp-plate provided with a loop adapted to be brought into separable holding engagement with said hasp-loop receiving member, and a key-operated locking mechanism within said oscillatory shell, but having a fixed relation to said shell, for preventing movement of said shell when said locking mechanism has been brought into a locked condition. 85

2. A lock comprising a main base-plate, a shell oscillatorily disposed upon said base-plate, a second shell within and having a fixed relation to said oscillatory shell, a hasp-loop engaging member upon said oscillatory shell, a hasp-plate provided with a loop adapted to be brought into separable holding engagement with said hasp-loop receiving member, a lock-stud within said oscillatory shell, a casing containing a locking mechanism also disposed within said oscillatory shell, but having a fixed relation to said shell, and a key-operated bolt extending laterally across said casing, said bolt normally having a portion in retaining engagement with said lock-stud to prevent movement of the said oscillatory shell. 95

3. A lock comprising a main base-plate having a circular depression, the wall-portion of said depression being provided with lug-receiving slots, a cylindrical shell oscillatorily disposed in the depression of said base-plate, said shell being provided with slots in registration with the slots in said base-plate, the slots of said shell being of greater lengths than the slots of said base-plate, a second cylindrical shell within said oscillatory shell, marginal fastening lugs extending from said second-mentioned shell through the slots in said oscillatory shell and into and through the slots in said main base-plate for securing said second-mentioned shell to said base-plate and with a fixed relation to and within said oscillatory shell, a hasp-loop engaging member upon said oscillatory shell, and a hasp-plate provided with a loop adapted to be brought into separable holding engagement with said hasp-loop receiving member. 115

4. A lock comprising a main base-plate having a circular depression, the wall-portion of said depression being provided with lug-receiving slots, a cylindrical shell oscillatorily disposed in the depression of said base-plate, said shell being provided with 125

- slots in registration with the slots in said base-plate, the slots of said shell being of greater lengths than the slots of said base-plate, a second cylindrical shell within said oscillatory shell, marginal fastening lugs extending from said second mentioned shell through the slots in said oscillatory shell and into and through the slots in said main base-plate for securing said second-mentioned shell to said base-plate and with a fixed relation to and within said oscillatory shell, a hasp-loop engaging member upon said oscillatory shell, a hasp-plate provided with a loop adapted to be brought into separable holding engagement with said hasp-loop receiving member, and a key-operated locking mechanism within said oscillatory shell, but having a fixed relation to said shell, for preventing movement of said shell when said locking mechanism has been brought into a locked condition.
5. A lock comprising a main base-plate having a circular depression, the wall-portion of said depression being provided with lug-receiving slots, a cylindrical shell oscillatorily disposed in the depression of said base-plate, said shell being provided with slots in registration with the slots in said base-plate, the slots of said shell being of greater lengths than the slots of said base-plate, a second cylindrical shell within said oscillatory shell, marginal fastening lugs extending from said second-mentioned shell through the slots in said oscillatory shell and into and through the slots in said main base-plate for securing said second-mentioned shell to said base-plate and with a fixed relation to and within said oscillatory shell, said oscillatory shell being further provided with a post-receiving slot and an upwardly extending post in alinement with said post-receiving slot, a post extending upwardly from said base-plate into and through the post-receiving slot of said oscillatory shell, a coil-spring mounted between and attached at its ends to said posts, a hasp-loop engaging member upon said oscillatory shell, and a hasp-plate provided with a loop adapted to be brought into separable holding engagement with said hasp-loop receiving member.
6. A lock comprising a main base-plate having a circular depression, the wall-portion of said depression being provided with lug-receiving slots, a cylindrical shell oscillatorily disposed in the depression of said base-plate, said shell being provided with slots in registration with the slots in said base-plate, the slots of said shell being of greater lengths than the slots of said base-plate, a second cylindrical shell within said oscillatory shell, marginal fastening lugs extending from said second-mentioned shell through the slots in said oscillatory shell and into and through the slots in said main base-plate for securing said second-mentioned shell to said base-plate and with a fixed relation to and within said oscillatory shell, said oscillatory shell being further provided with a post-receiving slot and an upwardly extending post in alinement with said post-receiving slot, a post extending upwardly from said base-plate into and through the post-receiving slot of said oscillatory shell, a coil-spring mounted between and attached at its ends to said posts, a hasp-loop engaging member upon said oscillatory shell, a hasp-plate provided with a loop adapted to be brought into separable holding engagement with said hasp-loop receiving member, and a key-operated locking mechanism within said oscillatory shell, but having a fixed relation to said shell, for preventing movement of said shell when said locking mechanism has been brought into a locked condition.

7. A lock comprising a main base-plate having a circular depression, the wall-portion of said depression being provided with lug-receiving slots, a cylindrical shell oscillatorily disposed in the depression of said base-plate, said shell being provided with slots in registration with the slots in said base-plate, the slots of said shell being of greater lengths than the slots of said base-plate, a second cylindrical shell within said oscillatory shell, marginal fastening lugs extending from said second-mentioned shell through the slots in said oscillatory shell and into and through the slots in said main base-plate for securing said second-mentioned shell to said base-plate and with a fixed relation to and within said oscillatory shell, said oscillatory shell being further provided with a post-receiving slot and an upwardly extending post in alinement with said post-receiving slot, a post extending upwardly from said base-plate into and through the post-receiving slot of said oscillatory shell, a coil-spring mounted between and attached at its ends to said posts, a hasp-loop engaging member upon said oscillatory shell, and a key-operated locking mechanism within said oscillatory shell, but having a fixed relation to said shell, for preventing movement of said shell when said locking mechanism has been brought into a locked condition.

8. A lock comprising a main base-plate having a circular depression, the wall-portion of said depression being provided with lug-receiving slots, a cylindrical shell oscillatorily disposed in the depression of said base-plate, said shell being provided with slots in registration with the slots in said base-plate, the slots of said shell being of greater lengths than the slots of said base-plate, a second cylindrical shell within said oscillatory shell, marginal fastening lugs extending from said second-mentioned shell through the slots in said oscillatory shell and into and through the slots in said main base-plate for securing said second-mentioned shell to said base-plate and with a fixed relation to and within said oscillatory shell, said oscillatory shell being further provided with a post-receiving slot and an upwardly extending post in alinement with said post-receiving slot, a post extending upwardly from said base-plate into and through the post-receiving slot of said oscillatory shell, a coil-spring mounted between and attached at its ends to said posts, a hasp-loop engaging member upon said oscillatory shell, and a key-operated locking mechanism within said oscillatory shell, but having a fixed relation to said shell, for preventing movement of said shell when said locking mechanism has been brought into a locked condition.

shell to said base-plate and with a fixed relation to and within said oscillatory shell, said oscillatory shell being further provided with a post-receiving slot and an upwardly extending post in alinement with said post-receiving slot, a post extending upwardly from said base-plate into and through the post-receiving slot of said oscillatory shell, a coil-spring mounted between and attached at its ends to said posts, a hasp-loop engaging member upon said oscillatory shell, a hasp-plate provided with a loop adapted to be brought into separable holding engagement with said hasp-loop receiving member, a lock-stud within said oscillatory shell, a casing containing a locking mechanism also disposed within said oscillatory shell, but having a fixed relation to said shell, and a key-operated bolt extending laterally across said casing, said bolt normally having a portion in retaining engagement with said lock-stud to prevent movement of the said oscillatory shell.

9. A lock comprising a main base-plate, a shell oscillatorily disposed upon said base-plate, a second shell within and having a fixed relation to said oscillatory shell, a plate mounted upon said oscillatory shell, a hook-shaped hasp-loop engaging post upon said plate, a rib extending upwardly from said plate, said rib having a downwardly inclined portion extending toward said hook-shaped post, and a hasp-plate adapted to ride upon said rib and having a loop adapted to be brought into separable holding engagement with said hook-shaped post.

10. A lock comprising a main base-plate, a shell oscillatorily disposed upon said base-plate, a second shell within and having a fixed relation to said oscillatory shell, a plate mounted upon said oscillatory shell, a hook-shaped hasp-loop engaging post upon said plate, a rib extending upwardly from

said plate, said rib having a downwardly inclined portion extending toward said hook-shaped post, a hasp-plate adapted to ride upon said rib and having a loop adapted to be brought into separable holding engagement with said hook-shaped post, and a key-operated locking mechanism within said oscillatory shell, but having a fixed relation to said shell, for preventing movement of said shell when said locking mechanism has been brought into a locked condition.

11. A lock comprising a main base-plate, a shell oscillatorily disposed upon said base-plate, a second shell within and having a fixed relation to said oscillatory shell, a plate mounted upon said oscillatory shell, a hook-shaped hasp-loop engaging post upon said plate, a rib extending upwardly from said plate, said rib having a downwardly inclined portion extending toward said hook-shaped post, a hasp-plate adapted to ride upon said rib and having a loop adapted to be brought into separable holding engagement with said hook-shaped post, a lock-stud within said oscillatory shell, a casing containing a locking mechanism also disposed within said oscillatory shell, but having a fixed relation to said shell, and a key-operated bolt extending laterally across said casing, said bolt normally having a portion in retaining engagement with said lock-stud to prevent movement of the said oscillatory shell.

In testimony that we claim the invention set forth above we have hereunto set our hand this 22nd day of August, 1923.

AUGUST GOERTZ.
FREDERICK GOERTZ.
